Attorney

UNITED STATES PATENT OFFICE

EDWARD H. ELLISON, OF JAMESTOWN, NEW YORK, ASSIGNOR TO ELLISON BRONZE COMPANY, INC., OF FALCONER, NEW YORK, A CORPORATION OF NEW YORK

GUN PORT

Application filed December 27, 1926. Serial No. 157,147.

This invention relates to an improvement in a gunport, and more particularly one that embodies gates which will swing in one direction, being rigidly held against movement in the other direction.

5 The provision in a wall of a porthole or orifice, through which the muzzle of a gun can be passed, is open to the objection that it can be used from either side of the wall, and 10 the primary object of this invention is to avoid this danger by providing a gunport which can be fixed in said porthole, and by which use can only be made of the porthole from one side of the wall.

15 A further object of this invention resides in the provision in a gunport of the type above mentioned gates which are normally held closed, but which can be opened from one side by the nozzle of a gun or other 20 weapon, and which, when closed, shield the person inside the wall.

25 Other objects of this invention will appear from a consideration of the following description taken in connection with the drawings which forms a part thereof, and in which

Fig. 1 is a front elevation of a gun port embodying one form of this invention; Fig. 2 is a horizontal sectional view taken along the line 2—2 of Figure 1, and illustrating 30 in dotted lines the position assumed by the doors when the port is in use;

Fig. 3 is a vertical section taken along the line 3—3 of Figure 1, and illustrating particularly the spring construction, by which 35 the doors are normally held closed; and

Figs. 4 and 5 are sectional views taken along the lines 4—4 and 5—5 of Figure 1, and illustrating the means for adjusting the tension of the door springs.

40 Such gunports may be installed for example in banks and similar buildings to protect the employees thereof from bandits or robbers. The gunports are suitably located in the walls which separate the employees from 45 the lobby or public portion of the bank. In the present instance, the device is shown installed in a tile or brick wall, being fixed in an orifice therein. For example, the gunport may be made of the proper size so that it can 50 be substituted for a brick or tile without re-

quiring any other alteration in the wall construction.

The gunport 10 is illustrated as mounted in an orifice 11 of a wall 12, the numeral 13 designating the outer face of the wall, in the 55 present case, the lobby side.

The gunport 10 proper is made up of two elements, viz: an outer member 14 and an inner member 15. The outer member 14 consists of an apertured face plate 16 which, as 60 shown in the drawings, extends beyond the edges of the orifice 11, and from which extend upper and lower flanges 17, 18, of such depth that they project through the orifice 11 and side flanges 19, which connect the flanges 17, 65 18, which flanges 17, 18 and 19 define the sides of a rectangular passage 20. The inner edges of the flanges 17 and 18 are cut away at the center to provide recesses 21, for a purpose to be set forth below.

70 The inner member 15 comprises a plate 22, the edges of which project beyond the opening of the orifice 11. Through the plate 22 extends a passage 23 defined at the top and bottom by parallel walls 24, and at the sides 75 by walls 25, preferably converging as shown particularly in Figure 2. The passage 23 projects into the recesses 21 formed in the flanges 17 and 18, the inner surfaces of the walls 24 coinciding with the inner surfaces 80 of the flanges 17 and 18 so that it forms a continuation of the passage 20.

85 The outer and inner members 14 and 15 are joined by screws 26, which pass through the corners of the plate 22 and enter the flanges 17 and 18. By means of the screws 26 the portions of the wall 12 around the orifice 11 are tightly clamped. Moreover the flanges 17 and 18 rest on the top and bottom walls of the orifice (see Figure 3), and the edges of 90 these flanges lie against the side walls of the orifice, (see Figure 2). Thus the gunport 10 is firmly fixed in the orifice 11, and can only be removed from the inner side of the wall 12.

95 The mouth of the passage 20 of the outer member 14 is closed by a pair of solid gates 30 pivotally supported upon posts 31. The posts 31 are carried by the flanges 17 and 18, extending into holes 32, 33, drilled therein.

100 The holes 32 in the flange 17 are consider-

ably larger in diameter than the posts 31, and receive collars 34 fixed on the upper ends of the posts 31 by pins 35. The holes 33 in the flanges 18, however, are formed to receive 5 snugly the lower ends of the posts 31. The collars 34 and posts 31 are free to turn in the holes 32, 33.

In each of the gates 30 are chambers 36, through which the posts 31 pass, and which 10 receive coil springs 37 surrounding the posts 31, and by which the gates 30 are normally closed. Each coil spring 37 is fixed to the gate 30 by passing its lower end into a pocket 38, opening into the chamber 36 of the gate 15 30. The upper end of the spring 37 enters a similar pocket 39 in the collar 34.

The collar 34 is provided with a plurality of radially arranged recesses 41, while threaded into the flange 17 are screws 42, the 20 tips 43 of which will enter one of the pockets 41 in the collar 34, (see Figure 3). The tension of each spring 37 is set before the outer and inner members are assembled by backing off the screws 42 until the tip 43 leaves the 25 opening 41 in the collar 34, turning the collar 34 in the proper direction until the proper tension has been reached, and then tightening the screw 42; the collar 34 being so fixed that one of the pockets 41 is opposite the screw 30 42, and will receive the tip 43, thus rigidly fixing the collar to the flange 17 and preventing any movement thereof under the urge of the spring 37. The collars 34 may be turned 35 by spanner wrenches, not shown, which engage holes 44 in the outer faces of the collars.

The gates 30 under the tension of the springs 37 close the passage 23, being fixed in the closing position by the contact of projections 45 on the gates with the flanges 19. 40 It will be noted that when the parts are assembled no screws are exposed, and that the gates cannot easily be opened from without. It is, however, very easy for anyone behind 45 the wall 12 to open the gates 30 by pushing the nozzle of a gun against them. The walls 25 of the passage 23 allow a considerable range to the holder of the gun, so that with a few such ports the lobby of the bank can be completely covered.

50 While one embodiment of this invention has been shown and described, applicant is not limited thereto, since it is obvious that other embodiments can be made without departing from the spirit and scope of this invention as set forth in the following claims.

Having thus set forth my invention, what I claim as new and for which I desire protection by Letters Patent is:

1. In a gunport adapted to be mounted in 60 an orifice and having a passage therethrough, a pair of gates normally closing said passage, posts on which said gates are pivotally mounted, said gates having chambers through which said posts pass, and springs in said 65 chambers for holding said gates closed.

2. In a gunport adapted to be mounted in an orifice and having a passage therethrough, a pair of gates normally closing said passage, posts on which said gates are pivotally mounted, said gates having chambers through which said posts pass, and coil 70 springs in said chambers and surrounding said posts for holding said gates closed.

In testimony whereof I have affixed my signature.

EDWARD H. ELLISON.
